UNITED STATES PATENT OFFICE.

JOHN SWINLAND, OF DULUTH, MINNESOTA.

UMBRELLA.

1,095,362.

Specification of Letters Patent.

Patented May 5, 1914.

Application filed February 27, 1914. Serial No. 821,429.

To all whom it may concern:

Be it known that I, JOHN SWINLAND, a citizen of the United States of America, residing at Duluth, in the county of St. Louis 5 and State of Minnesota, have invented certain new and useful Improvements in Umbrellas; and I do hereby declare the following to be a full, clear, and exact description of the invention, such as will enable others 10 skilled in the art to which it appertains to make and use the same.

My invention has for its object to provide an extremely simple and highly efficient umbrella; and, to this end, it consists of 15 the novel devices and combinations of devices hereinafter described and defined in the claims.

In the accompanying drawings, which illustrate the invention, like characters indicate like parts throughout the several views.

Referring to the drawings, Figure 1 is a view partly in elevation and partly in longitudinal section, with some parts broken away, showing my improved umbrella 25 open; Fig. 2 is a view corresponding to Fig. 1, but showing the improved umbrella closed; Fig. 3 is an elevation of the umbrella closed, with the stick telescoped therein; Fig. 4 is a view partly in elevation 30 and partly in longitudinal section of the umbrella as shown in Fig. 3; Fig. 5 is a plan view of the so-called crown cap and the associate parts of the umbrella, on an enlarged scale; Fig. 6 is a view in section, 35 taken on the line $x^6 x^6$ of Fig. 5; Fig. 7 is a detail view of the inner end of the umbrella stick and connected ends of the braces; and Fig. 8 is a view corresponding to Fig. 7, but showing a different method of 40 connecting the braces to the stick.

The numeral 1 indicates the umbrella stick, having, at its inner end, a head 2, and the numeral 3 indicates the ribs pivotally connected, at their radiating point, to a so-called floating crown piece 4, for opening 45 and closing movements. It is important to note that said crown piece 4 is entirely free from and independent of the stick 1. A cover 5 is secured to the ribs 3, extends over 50 the crown piece 4, and is clamped thereon by a crown cap 6, having a ground-engaging point, and secured to said crown piece by a set screw 7.

The ribs 3 are supported entirely from the 55 stick 1 by spreaders 8, pivotally connected, at their outer ends, to the intermediate por-

tions of the ribs 3, and pivotally connected, at their inner ends, to an outer runner 9 slidably mounted on the intermediate portion of the stick 1. The spreaders 8 are 60 further connected to the stick 1 by braces 10, pivotally connected, at their outer ends, to the intermediate portions of said spreaders, and pivotally connected, at their inner ends, to an inner runner 11 slidably mounted 65 on the inner end portion of the stick 1. Normally, the runner 11 is held between the head 2 and a spring-pressed catch 12 on the stick 1 against sliding movement. When the umbrella is open, the runner 9 is held in a position on the stick 1, to keep the umbrella open, by a spring-pressed catch 13 on said stick. 70

In the normal positions of the parts of the umbrella, as shown in Figs. 1 and 2, the 75 floating crown piece 4 is supported from the ribs 3 quite a distance outward from the inner end of the stick 1. To enable the umbrella to be folded into a relatively small and compact form, the latches 12 and 13 80 are released, and the stick 1 telescoped through the runners 9—11 into the umbrella, as shown in Figs. 3 and 4.

In Fig. 8, the runner 11 is shown secured to the stick 1 by screw-threaded engagement, in place of the latch 12. This screw-threaded engagement comprises external threads 14 cut on the stick 1, adjacent to the head 2, and internal threads 15 85 cut in the runner 11. Obviously, by rotating the stick 1, the threads 14 may be turned into or out of the threads 15, at will, to release the runner 11 from the stick 1, and permit sliding movement thereon. 90

While the floating crown piece is shown 95 applied to an umbrella having stiff ribs and stick, it is, of course, understood that the same may be applied to an umbrella having collapsible or telescoping ribs and stick, such, for example, as disclosed and claimed 100 in my Patent No. 1,088,743, granted March 3, 1914, entitled "Folding umbrella".

In some instances, it might be desirable to pivotally connect the inner ends of the braces 10 directly to the stick 1, in place of 105 pivotally connecting the same to a runner, as shown.

What I claim is:—

1. An umbrella comprising a stick, ribs connected at their radiating point, outward 110 of and free from the umbrella stick, a runner slidable on said stick, spreaders pivot-

ally connected to said runner and ribs, and braces pivotally connected to said stick and to said spreaders.

2. An umbrella comprising a stick, a floating crown piece entirely free from and independent of said stick, ribs pivotally connected to and radiating from said crown piece, a runner slideable on said stick, spreaders pivotally connected to said runner and to the intermediate portion of said ribs, and braces pivotally connected to the inner end of said stick and to the intermediate portion of said spreaders.

3. An umbrella comprising a stick, a floating crown piece entirely free from and independent of said stick, ribs pivotally connected to and radiating from said crown piece, inner and outer runners slideable on said stick, spreaders pivotally connected to said outer runner and to the intermediate portion of said ribs, braces pivotally connected to said inner runner and to the intermediate portion of said spreaders, and means for holding said runners against sliding movement when the umbrella is open.

4. An umbrella comprising a stick, a floating crown piece entirely free from and independent of said stick, ribs pivotally connected to and radiating from said crown piece, inner and outer runners slideable on said stick, spreaders pivotally connected to said outer runner and to the intermediate portion of said ribs, braces pivotally connected to said inner runner and to the intermediate portion of said spreaders, and

means for holding said runners against sliding movement when the umbrella is open, but operative to permit said stick to move into said umbrella through said runners when the umbrella is closed.

5. An umbrella comprising a stick, ribs connected at their radiating point outward of and free from the umbrella stick, inner and outer runners slideable on said stick, spreaders pivotally connected to said outer runner and to the intermediate portion of said ribs, braces pivotally connected to said inner runner and to the intermediate portion of said spreaders, and means for holding said runners against sliding movement when the umbrella is open.

6. An umbrella comprising a stick, ribs connected at their radiating point outward of and free from the umbrella stick, inner and outer runners slideable on said stick, spreaders pivotally connected to said outer runner and to the intermediate portion of said ribs, braces pivotally connected to said inner runner and to the intermediate portion of said spreaders, and means for holding said runners against sliding movement when the umbrella is open, but operative to permit said stick to move into said umbrella through said runners when the umbrella is closed.

In testimony whereof I affix my signature in presence of two witnesses.

JOHN SWINLAND.
